UNITED STATES PATENT OFFICE.

DAVID G. McCAA, OF LANCASTER, PENNSYLVANIA, ASSIGNOR TO THE ELECTRIC APPARATUS CO., OF PARKESBURG, PENNSYLVANIA, A CORPORATION OF PENNSYLVANIA.

RECEIVING SYSTEM.

Application filed July 29, 1924. Serial No. 728,832.

To all whom it may concern:

Be it known that I, DAVID G. McCAA, a citizen of the United States, residing in the city and county of Lancaster, State of Pennsylvania, have invented new and useful Improvements in Receiving Systems, of which the following is a specification.

My invention relates to a method of and apparatus for eliminating or reducing the effects of electrical disturbances in the reception of signals, telegraphic, telephonic or otherwise, represented by alternating current, and particularly alternating current or oscillations of radio frequency.

15 In accordance with my invention, the effects of static, atmospherics, strays and other natural or artificial disturbances, including other radio signals, are reduced or eliminated in a radio or other receiving system, whereby the desired signals are readily distinguishable or become intelligible notwithstanding the simultaneous existence of strong disturbing effects.

20 In accordance with my invention, the received energies representing both the desired signal and the disturbing effect are divided between reactive paths, one of which is employed for effecting the translation of the desired signals, and with another of which 25 is associated means for impressing thereon a part of the energy of the desired signals previously amplified, to cause a change of reactance, and thereby withholding from the signal-translating path the effects of the 30 undesired oscillations to greater degree than the effects of the signal-representing or desired oscillations.

35 My invention resides in the method and apparatus of the character hereinafter described and claimed.

40 This application is in part a division from my application Serial No. 601,455, filed November 17, 1922.

45 For an understanding of my method, and for an illustration of some of the forms my apparatus may take, reference is to be had to the accompanying drawing, in which:

Fig. 1 is a diagrammatic view of a receiving system embodying my invention.

50 Fig. 2 is a diagrammatic view of a modification.

Fig. 3 is a fragmentary diagrammatic view illustrating a modification of both Figs. 1 and 2.

55 Referring to Fig. 1, A represents the an-

tenna or other absorption structure of a radio or any other receiving system, connected through the variable inductance L and the primary P of an oscillation transformer to earth or other counter-capacity E, 60 the variable condenser C serving to tune the antenna path and the circuit including the primary P to the frequency of the oscillations produced in the antenna system by the energy absorbed from the natural or other medium. Inductively related to the primary P is the secondary S of an oscillation transformer. For tuning the secondary circuit, there is provided the usual tuning condenser C¹, whose terminals are connected to the grid circuit of the audion or other vacuum tube detector-amplifier V comprising the filament or cathode f, grid g, and anode or plate a. In the grid path may be connected the condenser C², shunted by the leak resistance r. In the anode circuit of the tube V is the source of current or battery B and a winding T, which may be the winding of a telephone receiver, or may be the primary of a transformer delivering the 70 plate circuit current or a component thereof to one or more stages of radio or audio frequency amplifying devices, as well understood in the art, the condenser C² and the resistance r being omitted when the amplification is to occur at radio frequency. 75 In shunt to the winding T may be connected the condenser C³ when the winding T is that of a telephone or the primary of an audio frequency transformer, the condenser C³ being omitted in the case where the winding T is the primary of a radio frequency transformer, all as well understood in the art.

80 As thus far described, the receiving apparatus is a usual one and per se is not my invention.

85 However, in accordance with my invention, there is connected in parallel with the primary P, or in any other divided or suitably related path or position therewith as 100 regards the antenna circuit or other path traversed by the oscillations of the desired signal and the simultaneously existing disturbing effect, a reactance, either capacitative or inductive, but preferably, as shown, 105 an inductive reactance L², whose amount may be adjustable as indicated. It is preferred that the resistance of the inductance L² shall be small as compared with its inductance. The magnitude of the inductance 110

L^2 is preferably so chosen that its reactive effect is great compared with that of the primary P for oscillations of the frequency corresponding with that of the desired signal, whereby, if the reactances L^2 and P only were present, the oscillations representing the desired signal attain a far greater magnitude in the primary P than in the inductance L^2 .

10 However, the reactance or inductance L^2 by itself is insufficient for my purposes, and there is connected in series therewith a variable condenser C^4 , which may be connected as indicated, and preferably, to the terminals of additional inductance in series with the inductance L^2 , this additional series inductance being indicated at L^3 , and may be in effect a continuation of the inductance L^2 and forming therewith in 15 effect an auto-transformer. For a given frequency of the oscillations representing the desired signal, the capacity of the condenser C^4 may be adjusted to a value with respect to the magnitude of L^3 , L^3 which 20 causes the reactance of the path L^3 , C^4 , L^3 in shunt to inductance L^2 for that frequency to vanish or become zero or substantially zero, whereby, under such condition and for such time, the effect is the same as 25 if the reactance of inductance L^2 were reduced to zero because the primary P is substantially completely robbed of signal-representing energy. That is to say, this 30 effect is the same as if inductance L^2 were short circuited or as if the leads to the two terminals of the inductance L^2 were brought into low resistance conductive contact with each other. The magnitude of the 35 capacity of the condenser C^4 for this condition is not that which would be given to the condenser C^4 to tune the control circuit L^2 , L^3 , C^4 by itself or when isolated, to the frequency of the oscillations representing the desired signal, but has been found to be 40 considerably greater, and for long wave lengths, as of the order of 13,000 meters, is substantially three or four times as great. In operation of the system, this large desired value of the capacity of the condenser 45 C^4 is found by trial by manually adjusting the condenser to produce optimum effect.

50 As indicated, however, in Fig. 3, it will be understood that the inductance L^3 in the antenna path may constitute a separate primary of an oscillation transformer whose secondary is the inductance L^2 in circuit with which is the condenser C^4 .

55 In all the arrangements shown herein there is coupled to the inductance L^3 a coil 60 D traversed by the amplified currents in the plate circuit of a thermionic amplifier V^2 , whose grid circuit includes the condenser C^5 and inductance S^4 , for tuning that circuit to the frequency of the received or desired oscillations. The winding S^4 is the secondary

of an oscillation transformer whose primary P^4 is included in the branch with the primary P , Fig. 1, or, as indicated in Fig. 2, is located directly in the antenna path in series with both branches therein. 70

The coil D is preferably rotatable or movable with respect to the coil L^3 for adjusting the amplitude of the oscillations of desired or signal frequency impressed by the coil D upon the control path or circuit comprising the inductance L^3 and condenser C^4 , and associated cooperative parts. 75

When the primary P^4 is traversed by feeble signal-representing oscillations it inductively affects the grid circuit of the amplifier V^2 , through the coupling P^4 , S^4 , thereby in turn causing an amplified signal-representing oscillation to inductively affect the circuit or path containing the condenser C^4 , with the result that when the signal-representing oscillations traverse the primaries P , P^4 , the reactance of the control path attains its normal or high value, forcing more signal-representing current through the primaries P , P^4 , the action being one of accumulation or building up as regards the effect of the coil D upon the control path or circuit containing the condenser C^4 , until finally the signal effects in the primary P have been increased to a maximum, due to the fact 90 that the reactance of the control path has attained a maximum.

The oscillations impressed by the coil D upon the control circuit or path are of the same frequency as those of the desired signal, and the circuit arrangement described is of a character utilizable for reception of sound waves, including speech, music, etc., or is utilizable in general for purposes of telephony. 100

When the coil D is impressing oscillations upon the control circuit or path, there obtains such strength in such path or circuit as to in effect open it, having the effect of increasing the reactance in shunt to the primary P , accordingly forcing more of the received signal energy through the primary P . 105

By the arrangement described, and as described in my aforesaid application, the effects of the relatively stronger static and other disturbances upon the signal-translating circuit are substantially relatively smaller than the effects thereon of the desired signal oscillations. The system is such 115 that the ratio of the effect upon the signal-translating circuit of the desired received oscillations to the effect upon the same circuit of the stronger static oscillations is far greater than the ratio of the received signal oscillations to the static oscillations as present in the antenna path without recourse to my invention. 120

While in the foregoing description currents of radio frequency have been assumed 125

and considered, it will be understood that my invention is not limited thereto, but in its broader aspect comprises a method of and apparatus for differentiating between currents, whether of audio or radio frequency, which may be of the same frequency but of different amplitudes; or comprises a method of and apparatus for reducing the difference between effects of such audio or radio frequency currents, whereby the weaker may produce a desired effect of greater relative magnitude than otherwise possible.

What I claim is:

1. The method of distinguishing between radio frequency oscillations representing a desired signal and oscillations representing a disturbing effect, which comprises subjecting to the influence of both sets of oscillations a signal-translating circuit and a control path including inductive and capacitative reactances, selecting in a circuit tuned to the frequency of said oscillations representing the desired signal a portion of the energy thereof, amplifying said selected energy, and impressing selected amplified energy upon said control path for varying its reactance for withholding to different degrees from said signal-translating circuit the effects of both said sets of oscillations.

2. Radio receiving apparatus for distinguishing between oscillations of radio frequency representing a desired signal and oscillations representing a disturbing effect, comprising signal-translating means influenced by both sets of oscillation, a control path including capacitative and inductive reactances and so disposed that changes in the reactance of said path cause said sets of oscillations to influence said signal-translating means to different degrees, means for amplifying a portion of the energy of the oscillations representing the desired signal, and means for impressing energy so amplified upon said control path to vary its reactance.

3. Radio receiving apparatus for distin-

guishing between oscillations of radio frequency representing a desired signal and oscillations representing a disturbing effect, comprising signal-translating means influenced by both sets of oscillation, a control path including capacitative and inductive reactances and so disposed that changes in the reactance of said path cause said sets of oscillations to influence said signal-translating means to different degrees, a circuit attuned to the frequency of the oscillations representing the desired signal and absorbing energy thereof, means for amplifying the energy absorbed by said tuned circuit, and means for impressing energy so amplified upon said control path for varying its reactance.

4. The method of distinguishing between fluctuating currents of different amplitudes, which comprises impressing the currents upon a current-translating circuit and upon a control path upon the magnitude of whose reactance depends the magnitude of effect in said translating circuit, amplifying energy of one of said currents, and impressing the amplified energy on the control path for changing said reactance for withholding from said translating circuit the effect of another of said currents to greater degree than the effect of said one of said currents.

5. Radio receiving apparatus for distinguishing between oscillations of radio frequency representing a desired signal and oscillations representing a disturbing effect, comprising signal-translating means influenced by both sets of oscillations, a reactive control path so disposed that changes in the reactance of said path cause said sets of oscillations to influence said signal-translating means to different degrees, means for amplifying a portion of the energy of the oscillations representing the desired signal, and means for impressing energy so amplified upon said control path to vary its reactance.

DAVID G. McCAA.
